PERFORATING MACHINE

Stig E. Rosenberg, Brockton, Mass.

Application July 19, 1938, Serial No. 219,980

2 Claims. (Cl. 164—93)

The present invention relates to perforating machines which are used in many industries and which have a wide use in the manufacture of shoes to ornament various forms of shoe uppers and parts thereof.

The die, particularly in the shoe industry, comprises one of a series of dies, the cutting edges of each of which are differently arranged to ornament the work pieces with different designs. 10 The series of dies comprise a repertoire from which each die is withdrawn for use and to which the die is returned after use. Some of the dies in the repertoire have been used for several seasons and, in consequence, the cutting edges have 15 become worn to such an extent that they do not lie in a horizontal plane.

In my application Serial No. 201,699, filed April 13, 1938, I disclosed a perforating machine having a perforating die and a die striking plate, 20 at least one of which is mounted to yield under resistance from the other, between which the work is penetrated and pierced by the cutting edges of the die, means for causing the cutting edges of the die to receive the entire penetrating pressure, and means independent of the cutting edges and coming into action at the moment they pierce the work for shouldering from the cutting edges of the die substantially the entire piercing pressure. With this construction and 25 mode of operation, it is essential that the cutting edges lie in a horizontal plane, thus precluding from use many old dies in the shoe manufacturers' repertoire.

The principal object of the present invention 30 is to produce a perforating machine embodying the desirable features of the invention disclosed in my application hereinbefore identified in a modified form in order that the shoe manufacturer may use the old dies in the repertoire 35 thereof.

To the accomplishment of this object, the various features of the present invention reside in certain constructions and arrangements of parts, hereinafter described and then set forth in the 40 appended claims, which possess advantages readily understood by those skilled in the art.

The various features of the present invention will be understood readily from an inspection of the accompanying drawing, in which:

50 Figure 1 is a detail view in front elevation showing the various features of the invention embodied in a perforating machine of the "Brockton" type in which the striking plate in moving downwardly impales the work upon the 55 upstanding cutting edges of the die, the means independent of the cutting edges for limiting the depth the cutting edges penetrate into the paper cutting bed being shown as located on the die;

55 Fig. 2 is a view similar to Fig. 1, but showing 60 the position of the parts after the cutting edges

of the die have penetrated and pierced the work and have penetrated to the limit into the paper cutting bed, and

Fig. 3 is a detail view in plan of the die, the stripper plate having been removed to show underlying parts.

For convenience in disclosure, the various features of the present invention have been illustrated and described as being embodied in the "Brockton" perforating machine, the construction and mode of operation of which is disclosed in my Patents Nos. 2,084,869, 2,093,099 and 2,108,447, issued, respectively, June 22, 1937, September 14, 1937 and February 15, 1938. Generally, the "Brockton" perforating machine, embodying the various features of the present invention, has the same construction and mode of operation as the "Brockton" perforating machine disclosed in my Patent No. 2,084,869, except that the pressure adjustment 35 disclosed in Fig. 3 20 of this patent has been eliminated to impart a constant stroke to the plunger or platen 21 therein.

In the embodiment of the invention illustrated in Fig. 1, the downwardly moving platen or plunger 4 of the "Brockton" perforating machine is provided with a groove 5 which receives a tongue on a plate 6 from which the die striking plate 7 is supported. The exposed face of the plate 7 is provided with a paper cutting bed 8, 30 it being understood that the machine is provided with the paper supply roll, the paper rewind roll and the paper feed disclosed in my Patent No. 2,084,869. The plunger is reciprocated vertically to cause the paper backed die 35 striking plate 7 to impale the work on the upstanding cutting edges of a die 9 which is mounted on a block 10, which is like the block 16 disclosed in Fig. 2 of my Patent No. 2,108,447, February 15, 1938.

For purposes of disclosure, the die 9 is illustrated and described as a combined ink-marking and perforating die of the type disclosed in my pending application, Serial No. 194,299, filed March 7, 1938. As usual in this type of die, the 45 perforating tubes 11 and the knife 12 (Fig. 3), are mounted, respectively, in a tube holder plate 13 and a knife holder plate 14 which are supported by a rest plate 15 carried in turn by a die block 16, the front face of which is provided with a handle 17 to facilitate the movement of the die into and out of the machine and from and to a position of pressure to and from a position of clearance.

Supported from the bottom of the die block 55 16 is a guide plate 18, the opposite side edges of which project beyond the corresponding edges of the block (Figs. 1 and 2), to form ledges 19 which slide in the guideways 20 of the tracks 21 projecting forwardly from the block 10.

In the "Brockton" perforating machine as heretofore constructed, a pressure adjustment was provided to permit the operative to adjust the length of the stroke of the plunger and thus 5 vary the pressure exerted by the striking plate in impaling the work upon the cutting edges of the die. In accordance with one of the features of the invention disclosed in my application Serial No. 201,699, this pressure adjustment 10 has been removed, and, accordingly, the plunger 4 has an impaling stroke of a constant length. But the normal distance separating the bottom 15 of the striking plate from the plane of the cutting edges of the dies has been made less than the length of the impaling stroke of the plunger 4, so either the die, the die striking plate, or both of them, must yield to prevent breakage.

For purposes of disclosure, Fig. 1 illustrates the die striking plate 7 as being mounted yieldingly on the plate 6, the die as being mounted 20 yieldingly on the block 10, and the block 10 as being mounted yieldingly on its supporting bed, which is like the bed 12 disclosed in my Patent 25 No. 2,108,447, but it will be understood by those skilled in the art that generally only one form 30 of the three yields illustrated in Fig. 1 need be employed at a time, although an unusual operating condition may require more than one of the yields and possible all three of them. While 35 one of the yields is illustrated as being embodied in the die, it may be more practicable to restrict the location of the yield to another readily removable part of the machine, such as between the plates 6 and 7 (Figs. 1 and 2), or on the bottom of the block 10, thus to avoid building a yield into each die of the interchangeable series.

Referring to Figs. 1 and 2, the die striking plate 7 is tapped to receive the screwed ends of bolts 22, the shanks of which pass loosely through 40 the plate 6 and a sheet of rubber 23 interposed between the plates 6 and 7, a head 24 on the bolt 22 serving to limit normally the position of the die striking plate 7 relatively to the plate 6.

Referring to Figs. 1 and 2, a sheet of rubber 45 25 is interposed between the bottom of the die block 16 and the plate 18, the sheet being held in place in the manner disclosed in my application Serial No. 201,699, filed April 13, 1938.

Referring to Figs. 1 and 2, a sheet of rubber 50 26 is interposed between the bottom of the block 10 and a plate 27, the rubber sheet 26 and the plate 27 being secured to the block 10 to form a yield therefor by posts 28 which are secured to the block 10 in a manner similar to the corresponding posts disclosed in my application Serial No. 201,699.

In accordance with the broad features of the invention disclosed in my Patent No. 2,093,099, the work is mounted upon a combined work 60 support and stripper plate 29, it being understood that the stripper plate is provided with apertures to permit the perforating, cutting and marking elements of the die to engage the supported work.

65 When the work is located on the work supporting plate 29 and the die is moved into the position of pressure, the "Brockton" perforating machine is thrown into operation to cause the striking plate to descend to impale the work 70 upon the cutting edges of the die. During the penetration and piercing of the work by the

cutting edges of the die, the entire pressure exerted by the striking plate is transmitted through the work to the cutting edges of the die, but as the cutting edges of the die engage the paper cutting bed at the moment they pierce the work, the cutting edges of the die and the striking plate are protected from injury. If, without more, the cutting edges of the die were to complete the penetration of the paper cutting bed and pierce it, the impact between the cutting edges of the die and the striking plate would cause serious damage thereto.

10 In order to limit the depth the cutting edges of the die penetrate into the paper cutting bed, the plate 9 on the die is provided with hardened 15 steel means having die striking impact surfaces arranged slightly above the plane of the cutting edges of the die. For purposes of disclosure, these hardened steel means are illustrated as elongated blocks, 30, 31, 32 and 33. The blocks 20 30, 31, 32 and 33 are secured rigidly to the plate 9 in a location to clear the work and to engage the striking plate 1 in a location to clear the paper cutting bed 8. The blocks operate through 25 openings formed in the stripper plate.

The shape and location of these hardened 30 steel means, broadly considered, is immaterial so long as they limit the depth the cutting edges of the die penetrate into the paper cutting bed 8. When they are mounted on the die, their impact 35 surfaces should be arranged in a plane slightly above the cutting edges of the die. If they were mounted on the striking plate 1, their impact surfaces would be arranged to contact some fixed part of the die clear of the work at a time when the cutting edges have penetrated into the paper cutting bed 8, but have not pierced it. Preferably, the means for limiting the depth the cutting edges of the die penetrate into the paper cutting bed 8 are interposed between the 40 striking plate and the die, whether or not they are all on the die, or all on the striking plate, or divided between them.

35 What is claimed as new, is:

1. In a perforating machine, the combination 45 with a perforating die and a die striking plate, at least one of which is mounted to yield under resistance from the other, between which the work is penetrated and pierced by the cutting edges of the die, a paper cutting bed for the die striking plate, and means for causing the cutting edges of the die to receive the entire work penetrating and piercing pressure, of means independent of the cutting edges and interposed between the die and the striking plate for limiting 50 the depth the cutting edges penetrate into the paper cutting bed.

2. In a perforating machine, the combination 55 with a perforating die and a die striking plate, at least one of which is mounted to yield under resistance from the other, between which the work is penetrated and pierced by the cutting edges of the die, a paper cutting bed for the die striking plate, and means for causing the cutting edges of the die to receive the entire work 60 penetrating and piercing pressure, of means mounted on the die independent of its cutting edges and arranged to engage the striking plate independent of its cutting bed for limiting the depth the cutting edges penetrate thereto.
